(57) **CLAIM**

The ornamental design for a rotatable and mountable light assembly for utility vehicle, as shown and described.

DESCRIPTION

FIG. 1 is a perspective view of a rotatable and mountable light assembly for a utility vehicle constructed in accordance with the present invention, with the wire broken away at the end to indicate indeterminate length;

FIG. 2 is a left side view of a rotatable and mountable light assembly for a utility vehicle as shown in FIG. 1;

FIG. 3 is a front view of a rotatable and mountable light assembly for a utility vehicle as shown in FIG. 1;

FIG. 4 is a right side view of a rotatable and mountable light assembly for a utility vehicle as shown in FIG. 1;

FIG. 5 is a rear view of a rotatable and mountable light assembly for a utility vehicle as shown in FIG. 1;

FIG. 6 is a top view of a rotatable and mountable light assembly for a utility vehicle as shown in FIG. 1; and,

FIG. 7 is a bottom view of a rotatable and mountable light assembly for a utility vehicle as shown in FIG. 1.
